R. BRENOT

CHAIN GRATE

Filed March 21, 1921

INVENTOR

René Brenot.

UNITED STATES PATENT OFFICE.

RENÉ BRENOT, OF PARIS, FRANCE, ASSIGNOR TO THE BABCOCK & WILCOX COMPANY, OF BAYONNE, NEW JERSEY, A CORPORATION OF NEW JERSEY.

CHAIN GRATE.

Application filed March 21, 1921. Serial No. 453,869.

To all whom it may concern:

Be it known that I, RENÉ BRENOT, a citizen of the Republic of France, residing at Paris, 23 Rue Eugène Carrière, France, have invented certain new and useful Improvements in Chain Grates, of which the following is a specification.

It has heretofore been proposed in chain-grate stokers with natural or forced draft, to use an arrangement for regulating the air supply in which the air is supplied to air-tight pressure chambers between the upper and lower runs of the grate, and is distributed thence in the various compartments, being allowed to escape through openings in an aperture plate or series of plates, over which the upper run of the grate travels.

In accordance with one feature of the present invention there are provided a plurality of independent pressure air-chambers each fitted with dampers by which the pressure and quantity of air supplied to different portions of the grate may be regulated. According to another feature of the invention these pressure air chambers are provided at their lower ends with hinged flaps which permit of the removal of clinker and the like and which may be used for working under combined forced and natural draught.

The invention is illustrated in the accompanying drawings in which the single figure is a longitudinal section through a chain grate embodying my invention and associated parts. In the drawing *c* denotes the independent pressure air chambers, three being shown. The air is led through a pipe and enters each of the chambers or compartments being controlled by a damper *r*. The air entering each compartment passes thence across the openings *o* in the plate or series of plates *B* over which the upper run of the grate *G* travels. As each compartment is equipped with a damper, the pressure in one may be varied without varying the pressure in the others. Likewise, the quantity of air can be regulated according to the state of the combustion at the different parts of the grate corresponding to each of the compartments.

Particles of coal and small portions of clinker which pass through the upper portion of the chain grate and collect in the compartments, can be cleared by way of each compartment by means of a hinged flap *V*

attached to the bottom thereof which flaps when closed form air tight closures. These flaps may be controlled either by hand or automatically by the motion of the stoker itself, or by means of a suitable mechanism. In the illustrative embodiment, the flap valves *V* are operated manually by mechanism comprising two or more cams 14 engaging each flap valve and secured to transverse shafts 15. One end of each shaft is provided with a lever 16, connected by a link 17 to a manually operated lever 18, each of which normally stands in the position 18, the several levers being in alinement in this position in the figure. Each lever 18 is provided with a pawl 21 engaging the teeth 22 of a segment 23. In the figure, one of the levers 18 is in the position 18', this lever controlling the left-hand flap valve *V*, which is open in this position of its lever 18. The pawls 21 serve to hold the levers 18 in this left-hand or normal position, the raising of a pawl 21 permitting the corresponding lever 18 to turn clockwise into the position 18' to permit the corresponding flap valve to drop open.

The arrangement of the flaps permits of working either under natural draught beneath the whole of the grate or under combined forced and natural draught in one or more of the compartments.

The air pressure compartments are preferably made hopper-shaped, as shown in the drawings, in order to reduce the size of the doors or flaps at the bottom of the compartments, and for also reducing the draft pressure against the same. Such reduction in size is particularly desirable where forced draft pressure is used which is considerable upon the surface of the door.

What I claim and desire to secure by Letters Patent of the United States is:—

In combination, a chain grate stoker, a plurality of compartments between the upper and lower runs of the grate and extending substantially across the entire grate, means for supplying air to said compartments, said compartments being provided with downwardly movable valves covering substantially the entire bottoms of said compartments for the discharge of dust and the like, and means for operating said valves.

BRENOT RENÉ.
